DESIGN FOR A VOLATILE MOTH EXTERMINANT

George C. Irwin, St. Louis, Mo.

Application January 25, 1943, Serial No. 109,341

Term of patent 14 years

To all whom it may concern:

Be it known that I, George C. Irwin, a citizen of the United States, residing in the city of St. Louis, State of Missouri, have invented a new, original, and ornamental Design for a Volatile Moth Exterminant, of which the following is a specification, reference being had to the accompanying drawing, forming a part thereof.

In the drawing:

Fig. 1 is a front elevational view of a volatile moth exterminant, showing my new design;

Fig. 2 is a view in rear elevation thereof;
Fig. 3 is a top plan view thereof;
Fig. 4 is a bottom plan view thereof, and
Fig. 5 is a view in side elevation of the volatile moth exterminant. The opposite side view is substantially identical with the side view of Fig. 5.

I claim:

The ornamental design for a volatile moth exterminant, as shown.

GEORGE C. IRWIN.
